United States Patent Office

Des. 192,503
Patented Apr. 3, 1962

192,503

LABORATORY STAND

William H. Bowers, Doylestown, Pa., assignor to Henry Troemner, Inc., Philadelphia, Pa., a corporation of Pennsylvania

Filed Sept. 27, 1961, Ser. No. 66,885

Term of patent 3½ years

(Cl. D16—1)

The FIGURE is a perspective view of a laboratory stand embodying my new design, with the portions shown in broken lines for illustrative purposes only.

I claim:

The ornamental design for a laboratory stand, substantially as shown and described.
